KEY CASE

George Boden, Waterbury, Conn., assignor to
 Buxton, Incorporated, Springfield, Mass., a corporation of Massachusetts

Application September 23, 1936, Serial No. 102,149

1 Claim. (Cl. 70—456)

This invention relates to improvements in key cases.

The invention is particularly directed to structural features of improvement in a key case of the type wherein the key holders are mounted in such a way that they may be conveniently removed and replaced, when desired. An example of this type of key case will be found in United States Letters Patent No. 1,908,846, granted May 16, 1933, on an invention of Carleton H. Howe. In the key case of such patent, the key holders are held against removal from their supporting member by a reciprocal locking device which can be manually moved against the opposing force of a spring to a position wherein the key holders, or any one thereof, may be removed from the supporting member.

In this type of key case, the spring is relied on to retain the reciprocal device in locking position. Removal of the spring from the case is possible and accidental loss of the spring can and has in some instances occurred. Without the spring, the locking device loses all of its effectiveness in insuring against loss of keys from the case. Thus, even though the locking device has been carefully designed to function effectively to prevent loss of keys, its effectiveness depends wholly on the spring. Without the spring the key case cannot function and is useless.

This invention has for its object to provide in a key case of the class described, a means for positively retaining the spring of the locking device in the key case against loss or removal, thereby providing added insurance against loss of keys from the case and a substantially fool-proof construction.

Other objects will appear as the detailed description proceeds and will be pointed out in the appended claim.

The invention will be disclosed for illustrative purposes in connection with reference to the accompanying drawing, in which:

Fig. 1 is a front elevational view of a key case embodying the invention,—the case being shown in open position;

Fig. 2 is an enlarged fragmentary elevational view thereof showing the key holder supporting means;

Figs. 3 and 4 are sectional views taken on the lines 3—3 and 4—4, respectively, of Fig. 2;

Fig. 5 is an end elevational view of the key holder supporting means taken from the left hand side of Fig. 2;

Figs. 6 and 7 are top plan views of the key holder supporting means showing the sliding mem-

ber thereof positioned to hold the key holders against removal and to permit removal of such key holders, respectively;

Fig. 8 is an elevational view of the sliding member; and

Fig. 9 is a perspective view illustrative of one step in the assembly of parts of the key holder supporting means.

In the drawing, I have shown my invention in connection with a key case of the type disclosed in the above named patent. This case includes a suitable folder of leather or the like, usually having a central section 10 and two flaps 11, foldable in overlapping relation over the central section and capable of being held in such relation by interengageable snap fastener elements 12 and 13. Secured to the central section 10, as by rivets 14, is a plate 15 of thin metal having its upper edge portion rolled over as shown to provide a hollow and partly cylindrical portion 16. The key holders 17, which may be of the form shown in the United States Letters Patent No. 1,968,989, granted August 7, 1934 on an invention of Warner R. Buxton, are provided with ball heads 18 which are mounted in the hollow portion 16 and enable the key holders to swivel as well as swing. The portion 16 has transverse slots 19 therein, one for each key holder. Each slot has a width such as to freely receive the neck portion 20 of the key holder and of such length as to enable the key holder to swing from its normal pendant position upwardly through an angle of about 180 degrees. Each slot at its upper end terminates with an enlarged portion 21 of a size and shape such as to enable the ball head 18 to pass therethrough. Normally, these enlargements are closed by the parts 22 of a locking device 23, which is mounted on the plate 15 to slide in the direction of the axis of tubular portion 16 from the position shown in Fig. 6 to that shown in Fig. 7. When the device 23 is positioned as shown in Fig. 7, recesses 24, provided in the upper edge of device 23, register one with each of the enlargements 21 and enable the key holders to be removed by withdrawing the ball heads 18 therethrough.

The locking device 23 is mounted in the same general manner disclosed in the above-named Howe patent. It has a part 25 which extends into a slot 26 formed in the lower wall of the tubular portion 16 and is held between the plate 15 and the long side wall of slot 26. This portion 25 has shoulders 27 one at each end thereof, which by abutment with the end walls of slot 26 limit the extent of sliding movement of the

device 23. A spring 28 tends to hold the locking device in the position shown in Fig. 6 and the right hand shoulder 27 then abuts the right hand end of slot 26, as shown in Fig. 4. To move the locking device from the position shown in Fig. 6 to that shown in Fig. 7, a finger piece 29 is provided on one end of the device, of the form shown in Fig. 5. The finger piece is bent forwardly at right angles to the device 23 and the upper part thereof serves to close the left hand end of tubular member 16 and the lower part extends below the member 16 so that it may be conveniently moved with the thumb nail. This finger piece is set flush into the end of the tubular member 16 and does not project beyond such end as in said Howe patent. This arrangement furnishes additional protection against accidental operation of the locking device and the lower portion of the finger piece is made small and located below portion 16 and against plate 15 for similar reasons.

The locking device 23 has an extension from the part 25 in the form of a narrow finger 30 the sides of which parallel the axis of the tubular portion 16 and are so spaced as to freely fit inside the spring 28. The spring seats at one end against the shoulder formed at the intersection of the finger 30 with the part 25. At the other end, the spring seats against two lugs 31 which are struck up from the left hand end wall of a recess 32, formed in plate 15 in underlying relation with spring 28 to provide clearance thereof. The finger 30 is long enough to span this recess 32 and extend beyond the same far enough to have its free end received between the lugs 31 which are spaced apart for this purpose. Thus, the spring 28 is, at all positions of the locking device, held on the finger 30. The only way in which the spring can be removed is to remove the finger 40 from between the lugs and this requires bending up of the finger from the device 23 or removal of the device from plate 15. Removal of the device from plate 15 means bending out the lower wall of tubular portion 16 from plate 15 and, 45 since both the portion 16 and finger 30 are made of stiff metal, the bending operations necessary to release spring 28 are not easily accomplished, much less are they likely to be effected accidentally which is what the invention seeks 50 to prevent.

The locking device and its spring are assembled before the tubular portion 16 of the plate is completely formed. With the plate 15 in the form shown in Fig. 9, the device 23 may readily be 55 slid into place. Then the part 25 thereof is swung

outwardly away from the plate, the rounded inner part of the device 23 engaging the upper rear rounded wall of tubular portion 16 as a pivot. The part 25 is thus swung into slot 26 and the right hand shoulder 27 thereof is moved against the right hand end of slot 26. The device 23 5 may be held thus positioned with the thumb of the left hand. The spring 28 is then slid in place on finger 30. Then with the thumb of the right hand the operator compresses the spring and at 10 the same time pushes downwardly on it to carry the finger between the lugs 31. The finger piece 29 serves to prevent the spring 28 from moving the locking device 23 to the right and holds it 15 properly positioned, while the portion 16 is completely rolled down into final form to hold the locking device in position.

The operation of the key case is the usual one and is fully disclosed in the above named Howe patent.

The invention, by preventing removal and particularly accidental loss of the spring of the locking device, makes the structure substantially fool-proof and affords added insurance against loss of keys caused by accidental escape of the key holders. Even if the key holders are not often lost, the escape of the spring from its position between its seats in the key case structure of said Howe patent, causes the user a great deal of annoyance. The spring, if it escapes, is liable to pop out 30 and move a considerable distance and, being small, is often difficult to find. Unless the spring is found and replaced, the key case is useless because, as has been described, the spring is the means which holds the locking device in locking 35 position. The invention saves the user from annoyances, such as described, and insures that the locking device will be held in place at all times except those when it is intentionally released.

What I claim is:

In a key case, a support for a key holder having an opening through which the key holder may be removed, a device shiftable from one position to another to cover and uncover, respectively, 45 said opening, a coil spring for retaining said device in one of said positions, seats one for each end of said spring and provided one on said support and one on said device, one seat comprising a pair of spaced lugs, and an extension from the 50 other seat passing entirely through the spring and between said lugs and overlapping said lugs in all positions throughout the range of movement of said device.

GEORGE BODEN.
